W. L. SCHULTZ.
NON-REFILLABLE BOTTLE,
APPLICATION FILED MAR. 20, 1908.

921,009.

Patented May 11, 1909.

UNITED STATES PATENT OFFICE.

WILLIAM L. SCHULTZ, OF NEW YORK, N. Y.

NON-REFILLABLE BOTTLE.

No. 921,009.

Specification of Letters Patent. Patented May 11, 1908.

Application filed March 20, 1908. Serial No. 422,346.

To all whom it may concern:

Be it known that I, WILLIAM L. SCHULTZ, a citizen of the United States, and a resident of New York, county and State of New York, 5 have invented certain new and useful Improvements in Non-Refillable Bottles, of which the following is a full, clear, and exact description.

This invention relates more particularly to 10 non-refillable means for bottles such as disclosed in my Patent No. 857,366, dated June 18th, 1907.

The primary object of the invention is to 15 provide simple and efficient means whereby the liquid may be readily poured from the bottle when filled and in which the parts are so constructed that the exit opening for the liquid in the bottle neck will be closed should an attempt be made to refill the bottle after 20 it is wholly or partly empty, and in which a member of the sealing means will be made to become positively locked in the bottle neck should an attempt be made to refill the bottle by creating suction in order to raise such 25 member from its sealing position.

A further object of the invention is to provide means which may be positively held in 30 position to prevent liquid passing from the bottle mouth into the body of the bottle when the latter is in certain positions; which may be readily applied to various forms of 35 bottles, and which is adapted to be used in connection with bottles adapted to contain liquids of various degrees of density.

With these and other objects in view, the 40 invention will be hereinafter more particularly described with reference to the accompanying drawings, which form a part of this specification and will then be pointed out in

the claims at the end of the description.

In the drawings, Figure 1 is a fragmentary 45 vertical section, partly in elevation, of one form of bottle embodying my invention. Fig. 2 is a detail side elevation of the stopper valve. Fig. 3 is an inverted plan view of the stopper valve. Fig. 4 is a detail view of the inner or float valve; and Fig. 5 is an inverted plan view of the valve shown in Fig. 4.

The body 10 of the bottle may have any 50 suitable form of neck 11, and in the upper part of said neck is a groove 12, and above the groove 12 is an inwardly-projecting rib 13, which is adapted to form a seat for a stopper valve or plug 14. This stopper 55 valve 14 may be of any suitable material,

and has its body portion 15 somewhat smaller than the bottle mouth 16, and the bottle mouth may have the usual stopper of cork or of any suitable material, or the mouth of the bottle may be sealed by the usual form of 60 cap or in any other desired way.

The valve or plug 14 has an enlarged flange or cap portion 17 which is slightly beveled upward, as at 18, to provide a suitable surface to rest upon a beveled seat 19 65 formed on the upper surface of the rib 13. By inclining the valve seat 19 as shown, it not only provides a good joint for the stopper valve 14, but also makes it more difficult to force a wire or other device past the cap 70 portion 17 of said valve 14.

The stopper valve 14 is provided with a shoulder 20 which is adapted to rest against the inner surface of the rib 13 and the body portion of said valve is provided with an angular groove 21 above the lower edge thereof in which is arranged a retaining device 22. This device 22 may be of any suitable form. As shown it comprises a band 23 the ends of 75 which are provided with a tongue and slot 80 connection, as at 24, to permit the band to be readily held in the groove 21, and projecting from the band are spring arms 25. These arms may be integral with the band as shown or made separate therefrom and said arms 85 are adapted to engage the annular groove 12 in the bottle neck in such a way that the stopper valve will have a limited outward movement to permit the liquid to be poured from the bottle, but which will hold the stopper valve against removal, there being any suitable number of such arms so as to properly hold the valve 14 in its proper position 90 in the bottle neck.

The body of the stopper valve 14 is provided with grooves 26 lengthwise thereof to 95 permit the liquid to flow more readily past the stopper valve, and the arms 25 may be positioned as shown, or they may be made to register with said grooves when the body 100 portion 15 of said valve is larger and fits the neck more closely so that the said arms may be forced into the grooves 26 of the body of the stopper valve while being inserted in the bottle neck, but which will permit the arms 105 to spring outwardly when said arms are in alignment with the groove 12. This latter arrangement makes it more difficult to force a wire or other device past the stopper valve to tamper with the inner sealing means. 110

To prevent the bottle from being refilled by creating suction in the bottle mouth, I provide a float or other valve 27, and above said valve arrange a weight 28. The weight 28 may be spherical or of any other desired shape and of any suitable material and is adapted to rest upon the upper surface of the inner valve 27 in such a way as to normally retain said valve in the position shown in Fig. 1. This valve 27 is hollow, and may be made of glass though other materials may be employed, and said valve has an enlarged head 29 with a flat upper surface and has a shouldered portion 30 which is adapted to engage a seat 31 formed in the bottle neck, and said seat as well as the valve may be ground so as to form a proper seal. The valve 27 is made very light and is provided with an extended portion 32 which has an opening 33 therein and has guiding ribs 34 which form recesses between said ribs so that the liquid may pass more readily by the valve body when the latter is in an open position, and said ribs serve to guide the valve in the bottle neck. The valve 27 might be closed in some instances though I prefer to make the same open as shown, so that when the liquid is poured it will enter the valve and the weight thereof will assist in unseating said valve, but when the bottle is placed in its normal position the said valve will be empty and will be held in position by the weight 28. If an attempt is made to raise the valve 27 from its seat by means of suction for the purpose of refilling the bottle the removal of the air above liquid in the body of the bottle will serve only to make the valve adhere to its seat, in which case the said valve becomes substantially fixed to the seat and cannot be easily removed so that it would be practically impossible to refill the bottle by this means and if an attempt were made to do so the bottle would become useless.

The bottle neck 11 is provided with an enlarged portion 35 and this enlarged portion is curved and so made as to form a guide for the weight 28. If the bottle is tilted in either direction the weight 28 will rest against the locking shoulder or curved portion 36 of the enlarged part 35 and will force the valve 27 to its seat and will prevent the same from being moved. If the weight 28 is shifted so that it will rest in the hollow or grooved portion 37 of the stopper valve 14 the said weight will assist in unseating the stopper valve 14 and by reason of the weight of the liquid and the lightness of the valve 27 the said valve 27 will become unseated and the liquid permitted to flow past said valve and past the stopper valve and out of the bottle mouth. By providing the part 35 with its locking shoulder as a part of the bottle neck a guide is not needed for the weight 28 as in my patent referred to.

65 From the foregoing it will be seen that sim-

ple and efficient means is provided whereby liquid of any suitable nature may be poured from a bottle and after the bottle is empty or partly so the said means will so act within the bottle neck as to prevent the bottle from being refilled; that the bottle neck is so made that it will serve to assist in holding one of the valves to its seat; and one of the valves is so made that if an attempt is made to raise the same from its seat by means of suction such means will only serve to cause the same to adhere more firmly thereto.

Having thus described my invention, I claim as new and desire to secure by Letters Patent:—

1. The combination with a bottle neck having a groove therein, of a stopper valve adapted to form a closure in the bottle neck, a locking device having a part thereof adapted to fit the groove in the bottle neck and hold the valve against removal, a hollow inner valve having an opening adapted to permit liquid to flow into said valve, said bottle neck having seats for the stopper and the inner valves, and a weight arranged between the inner valve and the stopper valve.

2. The combination with a bottle neck having a groove therein, of a stopper valve adapted to form a closure in the bottle neck, a locking device having arms adapted to fit the groove in the bottle neck and hold the valve against removal, a hollow float valve having an opening adapted to permit liquid to flow into said float valve, said bottle neck having seats for the stopper and the float valves, and a weight arranged between the float valve and the stopper valve.

3. The combination with a bottle having a groove therein and provided with a beveled valve seat above said groove, of a stopper valve arranged in the bottle and having a beveled portion adapted to form a closure with the valve seat, a locking device comprising a band held to the body of the stopper valve and having arms projecting outwardly therefrom the ends of which are adapted to enter the groove and prevent removal of said valve, a hollow valve having an opening adapted to permit the liquid within the bottle to flow therein and to assist in unseating said valve, said bottle having a seat for the hollow valve, and a weight arranged between the hollow valve and the stopper valve, said bottle having means for causing the weight to hold the float valve to its seat under certain conditions.

4. The combination with a bottle having a groove therein and provided with a valve seat above said groove, of a stopper valve arranged in the bottle and adapted to form a closure with the valve seat, a locking device comprising a band held to the body of the stopper valve and having arms projecting outwardly therefrom the ends of which are adapted to enter the groove and prevent re-

moval of said valve, an inner valve, and a weight arranged between the inner valve and the stopper valve, said bottle having a seat for the inner valve and provided with means 5 formed on the bottle neck for causing the weight to hold the inner valve to its seat under certain conditions.

5. The combination with a bottle having a groove therein and provided with a valve 10 seat above said groove, of a stopper valve arranged in the bottle and having grooves lengthwise thereof and adapted to form a closure with the valve seat, a locking device adapted to enter the groove and prevent re- 15 moval of said valve, a hollow valve having an opening adapted to permit the liquid within the bottle to flow therein and to assist in unseating said valve, and a weight ar- 20 ranged between the hollow valve and the stopper valve, said bottle having a seat for the hollow valve and provided with means

for causing the weight to hold the hollow valve to its seat under certain conditions.

6. The combination with a bottle having its neck provided with a valve seat, of a stop- 25 per valve arranged in the bottle and adapted to form a closure with the valve seat, means for preventing the removal of said valve, an inner valve, said bottle having a seat for the inner valve, and a weight arranged between 30 the inner valve and the stopper valve, said bottle being provided with an enlarged part and with a locking shoulder adapted to hold the weight against outward movement when in certain positions for the purpose set forth. 35

This specification signed and witnessed this nineteenth day of March A. D. 1908.
